UNITED STATES PATENT OFFICE.

ARTHUR J. ADAMS, OF CHICAGO, ILLINOIS, ASSIGNOR TO FULTON MANUFACTURING COMPANY, OF CHICAGO, ILLINOIS, A CORPORATION OF ILLINOIS.

FOOT-REST FOR GO-CARTS.

No. 927,089.

Specification of Letters Patent.

Patented July 6, 1909.

Original application filed May 7, 1908. Divided and this application filed January 6, 1909. Serial No. 471,025.

To all whom it may concern:

Be it known that I, ARTHUR J. ADAMS, a citizen of the United States, residing at Chicago, in the county of Cook and State of Illinois, have invented a new and useful Improvement in Foot-Rests for Go-Carts, &c., of which the following is a specification.

My invention relates particularly to adjustable foot-rests for go-carts or baby carriages, and my primary object is to provide a foot-rest of simple and improved construction and operating in an improved manner.

The invention is illustrated in the preferred embodiment thereof in the accompanying drawings, in which—

Figure 1 represents a longitudinal sectional view of a go-cart equipped with my improved foot-rest, the foot-rest being shown in the elevated position; Fig. 2, a broken 20 elevational view showing the front portion of the go-cart with the foot-rest in the lowered position; Fig. 3, a broken detail view of an automatically-locking, self-releasing foot-rest, the view corresponding with the lowered position of the foot-rest; and Fig. 25 Fig. 4, a similar view showing the foot-rest bar in a raised position.

In the construction illustrated, A represents the running-gear; B, pairs of wheels 30 journaled on brackets B^1 connected with the running-gear frame by pivots B^2 and adapted to fold beneath the running-gear frame in a well known manner; C, a handle connected by hinges c with the rear portion 35 of the running-gear frame; D, foldable brace-bars connecting the upper portion of the handle with the front portion of the running-gear frame and forming with the running-gear frame and the handle a triangular structure, said brace-bars serving also 40 as a means from which the seat may be suspended; E, a seat having its front portion suspended by links E^1 from the bars D and having connected with its lateral edges side- 45 flaps E^2 which are permanently secured to the bars D; F, a back having its lower portion flexibly joined to the rear portion of the seat, said back being adjustable to either a standing or reclining position by any suitable means and being equipped with side-

flaps F^1 (one shown) adapted for connection with the bars D when the back occupies the reclining position; and G, my improved automatically-locking, self-releasing foot-rest adjustably connected with the lower portion of the bars D.

The running-gear frame A may be of any suitable construction. Preferably, it comprises horizontally-disposed, longitudinally-extending side members a connected with cross members a^1 in a well understood manner.

The pair of wheels B at each side of the cart is adapted to fold beneath the running-gear frame in a well understood manner, and the brackets B are connected crosswise, in the extended position, by mechanism B^3 , which forms no part of the present invention.

The handle C comprises side members c^1 whose lower ends are connected with the hinges c , and whose upper ends are connected by a handle-round c^2 .

Each brace D comprises an upper member d and a lower member d^2 which are joined together by a pivot d^3 in a manner shown in detail in my application No. 471,024 filed of even date herewith, said application and the present application constituting divisions of my application No. 431,312, filed May 7, 1908. The upper end of each member d is connected, by a pivot d^4 , with the corresponding handle-bar c^1 ; and the lower end of each member d^2 is connected, by a pivot d^5 , with the front portion of the corresponding side bar a of the running-gear frame. The bars D are adapted to be flexed to permit the handle to be folded forwardly onto the running-gear frame, the members d and d^2 folding with relation to each other in this operation about the pivot d^3 , in a well understood manner.

The foot-rest G comprises a frame g adjustably connected with the lower front end- 85 portions of the bars d^2 ; a flexible apron g^1 extending from the front edge of the seat E and having side flaps g^2 and an end-flap g^3 suspended from the frame g and forming a chamber for the feet of the child; a foot-board g^4 on which the child's feet may rest 90

100

and may be supported when the foot-rest is in a lowered position; and a reversible boot or covering g^5 of the character described in my application No. 329,336, filed August 6, 5 1906. The frame g comprises sheet-metal members g^6 supported on the members d^2 ; members g^7 rigidly connected with the members g^6 and projecting forwardly therefrom; and a cross-rod g^8 connecting the front ends 10 of the members g^7 . The side-flaps g^2 are connected with the bars g^7 , as by means of rivets g^9 , and the flap g^3 is connected with the cross-rod g^8 . As best shown in Figs. 3 and 4, each member g^6 is provided with a 15 pair of cam-slots g^{10} , g^{11} , with which engage cam-studs g^{12} , g^{13} , respectively, carried by the corresponding bar d^2 . The cam-studs are headed, as shown, to prevent the members g^6 from becoming disengaged from the 20 cam-slots. The cam-slots of each pair may be described as long, straight cam-slots disposed at an angle to each other, the cam-slot g^{10} having an offset g^{14} , and the cam-slot g^{11} having an offset g^{15} . The offset g^{14} is located 25 adjacent to that end of the slot g^{11} which is not provided with an offset. When the foot-rest is in its lowered position, the cam-stud g^{13} engages the upper rear end of the cam-slot g^{11} . When the foot-rest is in an elevated 30 position, the cam-stud g^{12} engages the end of the offset branch-slot g^{14} and the cam-stud g^{12} engages the shoulder g^{10} at the base of the branch-slot g^{15} , as shown in Fig. 4. When it is desired to lower the foot-rest, it 35 may be lifted bodily, which movement will be permitted by the offset g^{14} accommodating the stud g^{12} while the offset g^{15} will accommodate the stud g^{13} . After the stud g^{12} is cleared by the shoulder g^{17} at the base of 40 the branch-slot g^{14} , the foot-rest may be dropped to the lowered position. When it is desired to raise the foot-rest to the elevated position, this is accomplished by raising the front portion of the foot-rest, at the 45 end of which movement the foot-rest will be automatically locked in the elevated position, as will be evident from Fig. 4.

It will be noted that the members g^6 are equipped centrally at their lower edges with 50 projections or bearings 1 which are adapted, when the cart is folded, to engage studs or bolt-ends 2, which extend inwardly from the running-gear frame-members a in the rear of the pivotal connection d^6 . When the go-55 cart is folded, the front bars d^2 swing downwardly about the pivots d^6 , so that the projections 1 will engage the studs 2 and automatically trip the foot-rest, permitting the same to drop to the position shown in Fig. 2. 60 From the foregoing description it will be understood that my foot-rest is of exceedingly simple construction, is strong and durable, and may be adjusted with the utmost facility. It may be stated, also, that the 65 manner of connecting the foot-rest with the

structure of the go-cart interferes in no way with the operation of folding the go-cart into compact form.

The foregoing detailed description has been given for clearness of understanding only, and no undue limitation is to be understood therefrom.

What I regard as new, and desire to secure by Letters Patent, is—

1. In a go-cart, the combination of a running-gear frame, a seat-supporting frame pivotally connected with the running-gear frame, a seat suspended on the seat-supporting frame, an independently adjustable foot-supporting frame comprising side members each provided with two cam-slots extending in angular relation to each other, and cam-studs carried by the go-cart structure engaging said cam-slots. 75

2. In a go-cart, the combination of a running-gear frame, a handle foldable with relation thereto, foldable brace-bars connecting the handle and running-gear frame, a seat suspended on said brace-bars, and an independently adjustable foot-support frame, comprising side members, each provided with a pair of cam-slots extending at an angle to each other and provided with offsets, and cam-studs carried by said brace-bars engaging said cam-slots. 90

3. In a go-cart, an independently adjustable foot-support comprising a frame having side members equipped at their extremities with cam-members, each of said cam-members having a pair of cam-slots extending at an angle to each other, one of said cam-slots having an offset near the adjacent end of the other cam-slot and the other of said cam-slots having an offset at its distant end, for the purpose set forth. 95

4. In a go-cart, an independently adjustable foot-support comprising a frame having side-members, equipped at their extremities with cam-members, each of said cam-members having a pair of angularly related cam-slots with shoulders corresponding with the elevated and depressed positions of the foot-rest, in combination with a pair of cam-studs on the go-cart structure engaging each pair of cam-slots, said cam-slots arranged to slide on said studs in shifting from one position to the other, thereby to bring one set of shoulders or the other to the supporting position, according to the adjusted position of said foot-rest. 100

5. In a go-cart, the combination of a running-gear frame, a handle foldable with relation thereto, a seat-support adapted to be folded with relation to the running-gear frame, an independently adjustable foot-support frame supported on said seat-support, and means carried by the running-gear frame for automatically tripping and lowering the foot-support frame in the operation of folding the cart. 115 120 125 130

6. In a go-cart, the combination of a running-gear frame, a handle foldable with relation thereto, a seat-support foldable with relation to said frame, an independently-adjustable foot-support frame, cam-connections between said foot-support frame and said seat-support, and tripping means on the foot-support frame and the running-

gear frame whereby the foot-support frame will be automatically tripped and lowered 10 in the operation of folding the go-cart.

ARTHUR J. ADAMS.
